Carl Miller

ATTORNEY.

UNITED STATES PATENT OFFICE

ARTHUR E. SORENSEN, OF AURORA, NEBRASKA

TICKET HOLDER

Application filed April 23, 1929. Serial No. 357,595.

The object of this invention is to provide a check or ticket holding device wherein checks or tickets of the type used by railway conductors, waiters, hat checkers, etc., may be securely retained therein, and readily removed therefrom, and automatically adjustable means whereby said holding device is adapted to retain clamped therein a plurality of checks or tickets, the number of which varies depending upon how many of said checks or tickets are removed therefrom or inserted therein.

Other objects of this invention are to provide a check or ticket holding device, that is small in size and hence easily carried, durable, efficient and foolproof.

A preferred embodiment of this invention is shown in the accompanying drawing wherein:—

20 Figure 1 is a perspective view of the ticket holding device.

Figure 2 is a sectional view of the same taken on lines 2—2, of Figure 1, and looking in the direction of the arrows.

25 The ticket holder consists of two pressed, or otherwise formed, metal retaining members 1 and 1', each comprising a curved top 2, side walls 3 and rear wall 4. Disposed within each of the retaining members 1 and

30 1' is a partition or base plate 5, said plate 5 being secured to the inner surfaces of the walls 3 and 4 in any desired manner, as for example by soldering or welding, and positioned parallel to the lower edges of said

35 walls. It is to be noted that the front edge of the base plate 5, shown in dotted lines in Figure 1, coincides with the front edge 2' of the curved top 2, and is secured thereto in the manner mentioned above.

40 Rigidly secured to the side walls 3 of the retaining members 1 and 1', and oppositely disposed with respect to each other, are semi-cylindrical members 6, the purpose of which is to be hereinafter described, having closed

45 tops 7 in substantial alignment with the top 2 of each of said retaining members, said semi-cylindrical members extending to the bottom edge of said side walls 3. The semi-cylindrical members 6 are secured to the side

50 walls 3 in the manner as noted above, and

define with said walls tubular sockets 8, each of which tubular sockets 8 are provided with rounded corners 8'.

The two retaining members 1 and 1' are oppositely disposed with the base plates 5 facing each other, and are permanently connected together by means of the tension coil springs 9 positioned within the tubular sockets 8, the ends of said coil springs 9 being rigidly secured to the tops 7 of the tubular sockets 8, as at 10, in any desired manner.

The checks or tickets 11 are positioned in said retaining members between the base plates 5 and the free portions of the side walls 3 and rear walls 4 and are clamped together by means of the coil springs 9 which are placed under tension when a plurality of checks or tickets are placed in the holder. As the tickets are removed one by one the remaining tickets are still retained in position by the coil springs 9.

To facilitate carrying of the ticket holder, a chain 12 is provided, the ends of which are centrally attached to the rear walls 4 of the retaining members 1 and 1' in any desired manner, as at 13. Carried by the chain 12 is a ring 14 having a smaller swivel socket ring 15 connected thereon, and through which swivel socket ring 15 the chain 12 is adapted to pass.

It is to be understood that the ticket holder shown on the accompanying drawing and described above is only a preferred embodiment thereof, and that the same is susceptible of various changes and modifications within the scope of the appended claim.

Having described this invention, what is claimed as new and is desired to secure by Letters Patent is:—

In a ticket holding device of the character described, a pair of oppositely disposed retaining members, each of said retaining members comprising a curved top, side walls and a rear wall, a base plate positioned with in each of said retaining members and arranged parallel with the free edges of said walls, the front edge of said base plate coinciding with the front edge of the curved top, a tubular socket rigidly attached to each side

wall of each of said retaining members and open at the bottom, a tension coil spring on each side of said retaining members and positioned within said tubular sockets, the ends of said coil springs being securely fastened to the top of said tubular sockets.

In testimony whereof I affix my signature.
ARTHUR E. SORENSEN.
